UNITED STATES PATENT OFFICE.

LOUIS S. D'ORSOGNA AND PIETRO CANE, OF PHILADELPHIA, PENNSYLVANIA.

PATTERN FOR DRAFTING GARMENTS.

1,078,576.

Specification of Letters Patent. Patented Nov. 11, 1913.

Application filed December 10, 1909. Serial No. 532,471.

To all whom it may concern:

Be it known that we, LOUIS S. D'ORSOGNA and PIETRO CANE, citizens of the United States, and residents of Philadelphia, Pennsylvania, have invented certain Improvements in Patterns for Drafting Garments, of which the following is a specification.

Our invention relates to the cutting of fabrics for use in the production of garments, and the object of our invention is to provide means that will enable us to prepare the fabric for use in the manufacture of such garments, particularly those intended to cover the upper portion of the body, so as to insure a perfect fit of such garments.

Our invention is fully shown in the accompanying drawings, in which:

Figure 1, is a view illustrating a piece of fabric as cut and designed to form the front of a coat, in this particular instance a woman's coat; Fig. 2, is a view illustrating such piece of fabric after it has undergone a shaping process possible with the use of our invention; Fig. 3, is a sectional adjustable pattern form constructed in accordance with our invention, and Fig. 4, is an end elevation of a portion of the same showing the manner in which it may be adjusted to the curves of the body.

All fabrics employed for use in the manufacture of clothing are flat, and in applying it to the human body after cutting it in the necessary sections to form a garment, it is necessary that it be stretched in some parts and shrunk in others in order that it may conform to the different curves of the hollows and prominences of the human form. Heretofore this has been done largely by guesswork upon the part of the tailor or cutter, for the amount to be stretched or shrunk in and the exact places for such stretching or shrinking is never precisely known. While it is possible to make measurements for these several points, it has been found in practice that such measurements never give the exact results necessary for a perfect fit or conformation of the fabric to the body. With our improved apparatus, it is possible to determine exactly the precise places at which the fabric must be stretched or shrunk, and the extent of stretching or "working in" as the shrinking operation is termed. We believe that we have avoided by said improvements the cause of former defects in the preparation

of garments, and have changed the guess-work heretofore in use to an unmistakable certainty.

In the pattern illustrated in Fig. 3, which may be the front of a body garment, we provide a structure comprising adjustable strips of flexible material so constructed that it may be disposed over the frame of the human body and curved as may be necessary to take care of the hollows or prominences of such body, and the particular feature of our invention is the arrangement of such pattern with special parts which may be stretched or contracted for the purpose of indicating the amount of material to be stretched or worked in.

Upon reference to Fig. 2, it will be noted that we have shown a number of spaces covered by dotted lines, and it is at these points that the stretching and shrinking or "working in" of the fabric is to be accomplished; the curved lines representing points where shrinkage is to be effected, and straight lines indicating points where stretching is to be effected. The marginal lines in full indicate the original shape of the fabric such as shown in Fig. 1, while the dotted marginal lines indicate the shape of the fabric after it has been changed to fit the particular person it is intended for. To determine the extent of this stretching, the following means are employed. The structure shown in Fig. 3, has a number of diagonally disposed bars 10; such bars being connected in all instances to the bars 11 forming the marginal lines of the pattern, and being confined by screw members 12. All of the sections are scaled in inches and fractions of an inch. When the pattern is placed upon the human body, the movably mounted sections are adjusted so as to cause such pattern to conform to all the hollows or prominences of such body, and Fig. 4 shows an approximate shape of the pattern in conforming to the side contour of a female figure, in which the portion indicated by the bracket *a* is that extending under the arm; the portion indicated by the bracket *b* is that directly at the waist, and the portion indicated at *c* is that passing over the hips. This particular part of the pattern has three sets of diagonal bars 10 to effect a curvature of the marginal bars 11, and therefore when the pattern is placed upon the body, these bars will be adjusted relatively to the portion over which such marginal bars pass.

2

There is a slight convexity at the point indicated by the bracket *a*, and to take care of this the diagonally disposed bars at this point will stretch along the marginal line 5 of the pattern. There is a decided concavity at the part indicated by the bracket *b*, and at such point the diagonal bars will be brought together, while at the part indicated by the bracket *c* there is some considerable convexity, and the diagonal bars 10 at this point will be separated to take care of the same. The amount of such separation is scaled from a fixed point at which the bars are disposed when the pattern is 15 lying flat, and hence it is a simple matter to ascertain the amount of contraction and expansion the marginal portion of the pattern has undergone in conforming to the body, so that when the same is brought to 20 its flat condition again to cut the garment, the difference between such flat condition and the curved condition will be known, and hence it will be possible to stretch or work in the material necessary to insure that the 25 section of cloth forming such portion of the garment conforms exactly to the human figure, and will therefore set or hang in place without bulging, wrinkling or compressing. The diagonal bars are adjustable 30 and are preferably anchored at the points 13 when the width of the particular section or portion of the pattern is determined, and the movement of the ends of said bars connected to the marginal sections or strips 35 of the pattern is in the arc of a circle of which the anchoring point is the center. These anchoring points may serve for a plurality of diagonal bars, independently movable.

40 While we have shown and described our structure with reference to one portion of a woman's garment, it will be understood, of

course, that similar pattern structures may be employed in connection with any portion of such garment, and with any other garment designed to closely fit the human form. 45

We claim:

In apparatus for preparing cloth sections subsequently connected together to form garments or pattern sheets from which such cloth sections may be cut, comprising a plurality of sectional adjustably jointed strips to fit over the human figure and conform to the contour and curvature of the same, the combination of marginal elements made up of a plurality of longitudinally adjustable pieces, clamping devices for securing said pieces together, bars diagonally disposed with respect to said adjustable marginal pieces and connected thereto by the 50 clamping devices for said pieces, said bars serving to hold the marginal pieces in position after an expansion or contraction in the length of said marginal pieces to cause the same to follow the contour of that portion of the body over which they are placed, a plurality of sections or pieces adjustably connected together and disposed substantially midway of the marginal pieces, said mid strip forming an anchorage for said 55 diagonal bars whereby the marginal sectional pieces connected to the same may be held in their adjusted positions with respect to said mid strip, and means for clamping the diagonal bars to said mid strip. 60

In testimony whereof, we have signed our names to this specification in the presence of two subscribing witnesses.

LOUIS S. D'ORSOGNA.
PIETRO CANE.
